UNITED STATES PATENT OFFICE.

EMIL HAHN, OF NEW YORK, N. Y.

LOCK.

1,020,978

Specification of Letters Patent. Patented Mar. 26, 1912.

Application filed December 12, 1911. Serial No. 665,212.

To all whom it may concern:

Be it known that I, EMIL HAHN, a subject of the Emperor of Austria-Hungary, residing in New York, borough of the Bronx, State of New York, have invented certain new and useful Improvements in Locks, of which the following is a specification.

The object of this invention is to provide a simple and effective lock in which the bolt may be operated from the outside of the door by means of a key, and from the inside without the use of any key.

For this purpose the invention comprises a bolt-casing suitably secured to the door at the inside of the same, a bolt adapted to slide in said casing and engage a keeper on the door-jamb, said bolt having a laterally-projecting handle, and a guide-pin and operating-pin projecting laterally therefrom through a slot in the bolt-casing, a vertical operating-rod pivoted at its upper end and extending at its lower end between the handle and the operating-pin, and means for rotating or swinging the said rod from the outside of the door.

In the accompanying drawing, Figure 1 is an elevation of the inside of a door and its jambs, in part, showing my lock applied to the door, Fig. 2 is a horizontal section on line 2—2 Fig. 1, Fig. 3 is a vertical section on an enlarged scale through the lock and adjacent part of the door; on line 3—3 Fig. 1, and Fig. 4 is a similar section showing a modified construction of the lock, as adapted to a Yale or other barrel lock.

Similar letters of reference indicate corresponding parts in the different figures.

To the door 9 is screwed or otherwise secured a bolt-casing or housing 10, having a longitudinal slot 11 in its outer wall. Within the housing 10 is slidably guided a bolt 12, the outer end of which is adapted when the bolt is thrown to engage a keeper 13 secured to the jamb 14, and thereby bolt the door. From the bolt a handle 15 projects laterally beyond the casing 10, thus permitting the bolt to be moved back and forth by hand at the inside of the door. Also from the bolt projects laterally and substantially parallel with the handle, but at a point nearer the nose of the bolt, an operating-pin 16. The pin 16 projects through the slot 11 to the outside of the casing 10, and by abutment with the rear end of the slot serves to limit the rear movement of the

bolt, and by abutment with the forward end of the slot when the bolt is thrown serves to limit its forward motion. The bolt is operated by means of a key having a vertical operating-rod 17, pivoted at its upper end to a link 18, which is in turn pivoted to the shank 19 of the key, having at its outer end a handle 20.

The operating-rod 17, link 18 and shank 19 may be of plain round rod, or of any section desired, which is adapted to be entered and withdrawn through an ordinary keyhole 21 of the door. Said keyhole is located above the bolt-casing and bolt, and the position of the key-hole and the spacing apart of the handle and operating pin are preferably so arranged that the operating-rod normally hangs between the forward position of the handle 15 and the rearmost position of the pin 16, as shown in Fig. 1. Thus when the rod is inserted for locking the door, it will by gravity assume a position behind the pin 16, and when inserted for opening the door it will normally assume a position in front of the handle 15.

The door is opened by inserting the key, composed of the parts 17, 18, 19, in the key-hole, whereupon the rod 17 falls in position to engage the handle 15. The key is then turned by means of its handle 20, whereby the rod is swung in backward direction against the handle and the bolt is drawn. For locking the door, the key is inserted in like manner, but turned in the opposite direction, whereupon it engages the pin 16 and moves the bolt forward.

The link 18 may be omitted, but it is preferably employed inasmuch as it adapts the key to doors of different thicknesses. In doors of ordinary or less than usual thickness the link 18 falls in line with the rod 17, as shown in Fig. 3, but in thick doors the link 18 remains in line with the key-shank in the key-hole, and the rod alone falls. The key is easily inserted in and withdrawn from the door by reason of its pivots which permit it to bend for locking, and to assume a straight condition for withdrawal. The shank is made of such length that the upper end of the rod 17 or link, as the case may be, is normally nearer the door than the outermost edge of the casing 10. By this means the rod is caused to bear against the casing-edge 22 as shown in Fig. 3, whereby the rod is retained by gravity in inward position, and does not easily fly outwardly.

under shocks to the door. Also for improving the security of engagement of the rod with the handle, the handle 15 is inwardly tapered, as shown in Fig. 3, so that under 5 the pressure of engagement therewith the rod 17 is retained in inward position against the casing-edge 22 and prevented by the handle from flying outwardly under shocks to the door.

10 In Fig. 4 the housing 23 of the Yale or other barrel lock is secured to the door in any suitable manner, and to the barrel 24 of the lock is secured at its inner end a head 25, in the same relative position to the 15 bolt and its handle and operating-pin as before described. The operating rod 26 is pivoted to the head 25 inwardly from the outer edge of the casing, as before described with reference to the operating-rod 17, 20 whereby the guiding and reliable engagement of the rod are secured. The key 27 of the Yale lock is inserted in the usual manner when it is desired to bolt or unbolt the door, and thereby the barrel may be turned 25 in either direction, so that the rod 26 is swung either against the handle or against the operating-pin, as the case may be, and the bolt withdrawn, or thrown, as desired.

For preventing the bolt from being 30 shaken out of position, and for securing the bolt against unintended movement, a friction spring 28 is employed, composed of two parts, longitudinally arranged at the upper

and lower portions of the bolt 12, and between the same and the housing 10, and 35 adapted to frictionally engage the housing, as shown in Fig. 2, thereby retaining the bolt with the desired degree of security in the position in which it is moved, but not preventing the easy movement of the bolt by 40 the operating-rod of the key.

I claim:

A lock, comprising a bolt-housing, a keeper, a bolt slidable in the housing and adapted to engage the keeper, said housing 45 having a longitudinal slot, an operating-pin projecting laterally from the bolt through said slot to the outside of the housing, an inwardly-tapering handle on said bolt, extending laterally therefrom at the 50 same side with the operating-pin, beyond the housing, an operating-rod, means for supporting the same at a point above the housing and inwardly from the outer-edge 55 of the same and between the forward position of the handle and the rearmost position of the operating-pin, and means for swinging said operating-rod from the outside of the door.

In testimony that I claim the foregoing as 60 my invention, I have signed my name in presence of two subscribing witnesses.

EMIL HAHN.
